UNITED STATES PATENT OFFICE

CHAUNCEY ALLAN LYFORD, OF EAST AURORA, NEW YORK, ASSIGNOR TO NATIONAL ANILINE & CHEMICAL COMPANY, OF NEW YORK, N. Y., A CORPORATION OF NEW YORK

REDUCTION OF ORGANIC NITRO COMPOUNDS

No Drawing.

Application filed August 24, 1929. Serial No. 388,270.

The present invention relates to the reduction of aromatic nitro compounds, and more particularly, to the reduction of meta-dinitro derivatives of aromatic hydrocarbons of the benzene series for the production of the corresponding meta-nitroamino derivatives.

It is an object of the invention to provide a process for the reduction of a meta-dinitro derivative of an aromatic hydrocarbon by treatment with an alkali metal sulfide in the presence of an organic liquid as a solvent, wherein the solvent is recovered with minimum losses, and a better yield of a purer reduction product is obtained.

Another object of the invention is the production of a pure meta-nitraniline by a process which is simple, efficient and economical in its operation.

Other objects of the invention will in part be obvious and will in part appear herein-after.

The invention accordingly comprises the several steps of the process herein disclosed and the relation of one or more of such steps with respect to each of the others thereof, as will be exemplified in the following disclosure, and the scope of the invention will be indicated in the claims.

In the reduction of m-dinitro derivatives of aromatic hydrocarbons, for example, meta-dinitrobenzene, by treatment with an alkali metal sulfide for the production of the corresponding m-nitroamino compounds, it has heretofore been the procedure to carry out the reaction by gradually adding an aqueous solution of the alkali metal sulfide to a suspension or solution of the meta-dinitro derivative in water or in alcohol. As thus performed, the process gives low yields of a reduction product of inferior purity. In commercial practice, the alcohol used in the process is recovered by distillation and rectification, which has the disadvantage that it incurs losses of solvent and requires considerable time and labor for its performance. In general, the crude reduction product resulting from either process must be purified for use in the manufacture of dyestuffs.

According to the present invention, it has been found that the reduction of meta-dinitro

derivatives of the aromatic hydrocarbons by treatment with an alkali metal sulfide may be performed in the presence of a two phase liquid system comprising water and an inert organic liquid which is substantially immiscible with water, the organic liquid being a solvent for said dinitro derivative. The organic liquid employed is usually and preferably, although not necessarily, a solvent for the nitroamino compound produced. The organic liquid employed is also preferably volatile in steam, and can therefore be readily recovered with little, if any, loss; and further, no rectification is required to adapt it for re-use in the process.

Organic liquids which are suitable for use in the practice of the present invention are the chlorinated hydrocarbons, for example, carbon tetrachloride, tetrachlorethane, chlorbenzene, and particularly aromatic hydrocarbons, e. g., benzene, toluene, solvent naphtha, etc., individually or in admixture. By the term "alkali metal sulfides" as used throughout the specification and claims, it is intended to include the hydrosulfides, sulfides, and polysulfides of ammonium as well as of the alkali metals.

In the practice of the present invention, the dinitro body is dissolved in the organic liquid, and to the resulting solution or mixture, while well agitated or stirred, an aqueous solution of the alkali metal sulfide is added. Considerable heat is generated during the addition of the sulfide. If the temperature increases sufficiently to boil the reaction mixture, the organic liquid may be permitted to distil off, and may be condensed and collected, or it may be condensed and returned to the reduction mass. When the reduction is completed, the organic liquid remaining in the mixture is distilled off and collected, and the reduction product is recovered from the residual aqueous liquors in any suitable manner. A product of excellent purity can be thus obtained in excellent yields.

For the best results, both as to yields and quality of the reduction product, the sulfide is added to the mixture of the water and the solution of the dinitro compound in the or-

ganic liquid as quickly as operation conditions will permit, the temperature of the reaction mixture being maintained at or near its boiling point, but the order may be reversed and the organic liquid containing the m-dinitro compound may be added to the alkali metal sulfide solution. The time required for the addition of the sulfide will depend on operating factors such as the size 10 of the batch, the volatility of the organic liquid, the concentration of the reaction mass, the violence of agitation, etc. Preferably, the sulfide employed is added in aqueous solution. It is also preferable that the organic liquid employed is one which boils at about 90° to 100° C. Preferably, the amount of organic liquid employed is sufficient to dissolve most or all of the dinitro body and the total amount of water present is sufficient 20 to dissolve, when hot, the resultant nitro-amino compound.

As illustrative embodiments of the manner in which the process of the present invention may be practiced, the following examples 25 are given. The parts are by weight.

Example 1.—A polysulfide (Na_2S_x) solution is prepared by heating 180 grams of a 7 per cent Na_2S solution with 10 grams flowers of sulfur.

30 25 grams of technical m-dinitrobenzene (85 per cent purity) and 40 grams solvent naphtha are placed in a reactor equipped with an agitator and a reflux condenser. The mixture is warmed to about 60° C. until complete solution occurs. 1000 grams hot water is then added. The m-dinitrobenzene solution is heated to boiling (about 94°-95° C.) and the hot polysulfide solution is rapidly added thereto. The sulfide is all added 35 within a period of about 2 minutes. The reaction of the polysulfide generates enough heat to appreciably increase the rate of boiling of the reaction mass. Reduction of the m-dinitrobenzene to m-nitraniline takes place 40 almost immediately.

The m-nitraniline may be isolated in any suitable manner, for example, by filtering the hot solution to eliminate free sulfur, and distilling off the solvent naphtha with steam. 50 The m-nitraniline remains behind dissolved in the aqueous portion from which solution it crystallizes out on cooling, and is filtered and washed. The product thus obtained is in the form of bright yellow crystals.

55 *Example 2.*—25 grams of technical m-dinitrobenzene (91 per cent purity), 60 grams of solvent naphtha and 900 grams water are combined and heated to a temperature of about 90°-92° C. in a reactor equipped with a Liebig condenser. To this solution is added within a period of about 5 minutes, a polysulfide (Na_2S_2) solution prepared from 5.5 grams sulfur and 191 grams of a 7 per cent Na_2S solution. The process is carried out 60 according to example 1, except that the sol-

vent naphtha is permitted to distil off during the reaction. After the reaction is completed, any remaining solvent naphtha is steam distilled off and the free sulfur is filtered off from the hot solution. Upon cooling, the m-nitraniline crystallizes out of solution in the form of bright yellow crystals of exceptionally high purity, having a melting point of about 113.4° C. The yield is 70 about 90 to 95 per cent. The product is usually sufficiently pure, without further purification, for use in making azo dyestuffs. 75

In the above examples, the aqueous portion from which the m-nitraniline crystallizes out 80 contains sodium thiosulfate which can be recovered in any suitable manner, as by evaporating off the water.

By the use of an immiscible solvent of suitable boiling point, the reducing agent can be rapidly added without producing excessive 85 heating. Further, the temperature is automatically prevented from rising too high by the evaporation of the solvent which may be refluxed or may be permitted to distil off with the steam generated.

90 The process of the present invention is applicable to the reduction of pure or purified, as well as technical, dinitro derivatives without substantially affecting the yield or the quality of the final product. In place of meta-dinitrobenzene, other dinitro compounds may be reduced, for example, the meta-dinitro derivatives of toluene, xylene, etc.

I claim:

1. In the production of an aromatic nitro-amino derivative, the process which comprises subjecting a meta-dinitro derivative of a hydrocarbon of the benzene series to the action of an alkali metal sulfide in the presence of water and of an inert, water immiscible organic liquid which is a solvent for the m-dinitro derivative. 100

105 2. In the production of meta-nitraniline, the process which comprises subjecting meta-dinitrobenzene to the action of an alkali metal sulfide in the presence of water and of an inert, water immiscible organic liquid which is a solvent for the meta-dinitrobenzene. 110

115 3. In the reduction of meta-dinitrobenzene, the process which comprises quickly introducing a water-soluble sulfide into a heated mixture of meta-dinitrobenzene and water in the presence of an inert, water immiscible organic hydrocarbon liquid which is a solvent for the m-dinitrobenzene. 120

125 4. The process which comprises dissolving m-dinitrobenzene in solvent naphtha, treating the solution with an aqueous sodium polysulfide solution to produce m-nitraniline, distilling off the solvent naphtha, filtering the resulting aqueous solution of m-nitraniline, and crystallizing out the m-nitraniline from the filtered aqueous residue.

130 5. In the production of m-nitraniline by the reduction of m-dinitrobenzene with an

alkali metal sulfide, the improvement which comprises carrying out the reduction in the presence of a two phase liquid system comprising water and an inert organic liquid which is substantially immiscible with water and in which organic liquid the m-dinitrobenzene is soluble.

6. In the production of a meta-nitro-amino compound by the reduction of a meta-dinitro derivative of a hydrocarbon of the benzene series with an alkali metal sulfide, the step which comprises carrying out the reaction in the presence of water and of an inert organic liquid which is a solvent for the dinitro body and which is substantially immiscible with water.

7. A process of preparing meta-nitraniline which comprises subjecting meta-dinitrobenzene dissolved in solvent naphtha to the action of an aqueous solution of a sodium sulfide.

8. The process which comprises dissolving m-dinitrobenzene in solvent naphtha, treating the solution with an aqueous sodium polysulfide solution to produce m-nitraniline, extracting the m-nitraniline with hot water as it is produced, distilling off the solvent naphtha, filtering the resulting hot aqueous solution of m-nitraniline, and crystallizing out the m-nitraniline from the filtered aqueous residue.

9. In the production of meta-nitraniline by the reduction of meta-dinitrobenzene with an alkali metal sulfide, the improvement which comprises carrying out the reduction in the presence of a two phase liquid system comprising water and solvent naphtha.

In witness whereof, I have hereunto set my hand.

CHAUNCEY ALLAN LYFORD.
